(57) CLAIM

The ornamental design for an air freshener package, as shown and described.

DESCRIPTION

FIG. 1 is an isometric view of an air freshener package;
 FIG. 2 is a front view of the air freshener package;
 FIG. 3 is a left view of the air freshener package;
 FIG. 4 is a back view of the air freshener package;
 FIG. 5 is a right view of the air freshener package;
 FIG. 6 is a top view of the air freshener package; and,
 FIG. 7 is a bottom view of the air freshener package.
 The broken lines shown in the drawings are for illustrative purposes only and form no part of the claimed design.

1 Claim, 3 Drawing Sheets(56)
